CLAIM

The ornamental design for a head wearable device, as shown and described.

DESCRIPTION

FIG. 1 is a perspective view of the ornamental design; FIG. 2 is a front view of the ornamental design; FIG. 3 is a back view of the ornamental design; FIG. 4 is a side view of the ornamental design; FIG. 5 is another side view of the ornamental design; FIG. 6 is a top view of the ornamental design; FIG. 7 is a bottom view of the ornamental design; and, FIG. 8 is a perspective view of the ornamental design in an expanded form.

The dashed lines are also for purposes of showing environmental structure and operational use only, and form no part of the claimed ornamental design.
